LOAD BEARING STRUCTURE

This invention relates to a load bearing structure having a horizontal platform for the load and a sub-structure between said platform and the ground or floor.

The main object of the invention is to provide a structure which can be produced cheaply and quickly, primarily for use in theatres and exhibitions and which are easily transportable. A further object is to provide a structure which when not in use, can be stored conveniently in a small space and which can be set up for use easily. Another object is to provide a construction in which the sub-structure can take various forms and built to different heights using standard units.

According to the invention there is provided a load bearing assembly comprising a horizontal platform mounted on a sub-structure said sub-structure consisting of a plurality of vertical hollow units, each unit comprising a rectangular sheet of substantially rigid material scored along longitudinal lines into rectangular sections and folded and joined to form a box tube unit.

The units used can be of identical form, or units of different form can be built up as a super-structure.

The adjacent sides of units can be secured together either temporarily or permanently, or a means such as a lattice structure, can be used to hold the units together.

In an embodiment, each unit consists of a rectangular sheet divided by score lines into three main sections of identical width and extending therefrom, three further sections also divided by score lines, two of which are identical and constitute strips for the joining together of the blank, the three sections of identical width being folded in the same direction relatively through 90° and the other three folded through angles such that the vertical edge of the end section thereof abuts the score line between the first and second of the three identical sections.

In another embodiment each unit consists of a rectangular sheet divided by score lines into four main sections of identical width and three further sections also divided by score lines, two of which are of the same width and joined by a wider section, said two serving as fastening strips for the joining together of the unit, the first four folding sections being folded in the same direction to form a square box structure and the three further sections folded in a substantially Z-shaped manner, the two of the same width being secured to adjacent surfaces of the box forming sections.

Each unit may also consist of a rectangular sheet having three sections divided by score lines and folded in Z-shaped manner, the end sections being of identical width and the median section wider than said end sections.

In a further embodiment each unit consists of a rectangular sheet having four main sections divided by score lines and of identical width and, three further sections divided by score lines and extending from one edge of an end main section, the end sections of the further sections being of identical width, the four main sections being folded in the same direction to form a square box structure with the one further section adjacent the one main section secured thereto, the intermediate section extending obliquely from the one main section towards its adjacent main section with the other end section secured to said adjacent main section.

The load distributing surface of the load bearing structure in accordance with the invention is preferably a wooden plate or board which is placed, in the simplest case, on to the folding units.

The structure of the invention thus consists of constructional elements or units which are supplied or stored flat and which are made from blanks or sheets preferably from corrugated cardboard and which, after folding up along the scored or fold lines on the blank and after fixing together or insertion, are given their stability and, form the desired configuration of the sub-structure. The connecting of the individual units can be by stitching, by staples, by adhesives, by adhesive strips or the like. The load distributing surface needs to be placed on assembled units. If however, on the contrary, bevelled or stepped plane load bearing structure is used, then the surface board can be fixed. The provision of theatre, film exhibition and similar structures is considerably simplified, since plane load bearing structures can be used which can be assembled on the site by simple means from industrially finished constructional units. The units, i.e., the sheets, can be standardized for economic reasons. They can be identified by different colouring according to their intended use and can be delivered and stored in stacks. After the joining together of the units their outer sides or visible surfaces can be painted, pasted on or clad with any desired material in accordance with the intended effect. After the termination of use, the units can be discarded. Thus, not only is the erection and structural alteration of the structures simplified, but also the demolition thereof. More especially storage space is economized.

Preferred embodiments according to the invention will now be described with reference to the accompanying drawings in which:

FIG. 1 is a top perspective view of a load bearing structure in the form of a three-step platform;

FIG. 2 is a view similar to FIG. 1 of a platform;

FIG. 3 shows a lattice-work for the structure according to FIG. 1,

FIG. 4 is a perspective view of a blank for producing load bearing structures;

FIG. 5 shows the structure according to FIG. 4 in the folded-up condition; and

FIGS. 6 to 10 show various structures in the folded-up condition for producing load bearing structures according to the invention.

FIG. 1 of the drawings shows a load bearing structure 10 having a load distributing surface in the form of a board 11 (only part of which is shown) and which rests on a plurality of folding plate structures 12 of corrugated cardboard, arranged with their longitudinal axis perpendicular to the load distributing surface. The structures 12 are inside a lattice-work 13 providing a cellular structure which also is made from corrugated cardboard and which, as shown in FIG. 3 consists of sheet or strip blanks 31, 32 and 33 which interengage by providing cuts or incisions 34 in from opposite edges of blanks 31 and cuts or incisions 35 in the blanks 32 at positions corresponding to the cuts or incisions 34, the blanks 33 having no cuts or incisions. Thus, a plurality of rectangular cells are provided by the lattice.

Individual folding structures have, as FIGS. 5 to 9 show, a different configuration and folding arrangement. They consist, as shown best in FIG. 4 of a rectangular blank 40 consisting of corrugated cardboard.

In the case of the embodiment shown in FIG. 4, four folding sections 41, 42, 43 and 44 of identical width are provided, followed by three further folding sections 45, 46 and 47. If the sections are folded along score lines 48 applied on the blank, namely the first four folding sections in the same direction through respectively 90° and the remaining three folding sections through angles other than 90° in a substantially S or zig-zag manner in the direction of the third section 43, there then is produced an approximately parallelepiped hollow body, (FIG. 5). The sections 45 and 57 can be connected with the sections 41 and 43 for example by stitching staples 4a or by adhesive, so that a rigid structure capable of supporting loading in its longitudinal axial direction is formed.

FIGS. 6 to 10 show similar folding structures 60, 70, 80, 90 and 100 which are also constructed from a rectangular sheet of material, e.g., corrugated cardboard and which are of standard dimensions. In the case of the folding structure 60, FIG. 6, three folding sections 61, 62 and 63 of identical width are provided, to which three further folding sections 64, 65 and 66 are connected extending from the free longitudinal edge of the section 63, the sections 64 and 66 being of the same width and serving as fastening strips for producing the box like support. The first three folding sections 61, 62 and 63 are folded on score lines in the same direction each through 90° with respect to its adjacent section and the sections 64, 65 and 66 are folded on score lines so that the section 66 lies contiguously on the inner surface of the section 61 at its end adjacent the section 62, with the section 65 oblique with respect to its adjacent sections 64, 66.

FIG. 7 shows a folding structure 70, comprising only three folding sections 71, 72 and 73 folded in a Z or zig-zag manner.

In the example shown in FIG. 8 the structure 80 comprises four folding sections 81, 82, 83 and 84 of the same width and three folding sections 85, 86 and 87, the sections 85, 87 being of less width and being for joining respectively to the sections 81, 82. The first five folding sections 81, 82, 83, 84 and 85 are folded in the same direction each through 90° with respect to its adjacent section and the last two sections 86, 87 are folded through oblique angles towards the second folding surface 82 so that sections 85, 81 and 87, 82 can be joined.

In the case of the structure 90, shown in FIG. 9, two sections 91 and 92 of identical width are provided and subsequent thereto, three sections 93, 94 and 95, of which the sections 93 and 95 are of the same width united by the shorter section 94. The first two sections 91, 92 folded through 90°, the following folding sections through different angles so that the free edge of the section 95 is received at the score line between the sections 91, 92.

The folding structure 100 shown in FIG. 10 has a section 101 to which there are linked four folding sections 102, 103, 104 and 105, of which the sections 102, 104 are of identical width and are folded in substantially U-fashion towards the folding section 101 the section 103 forming the base of the U. The folding section 105 is folded outwardly and forms a fastening strip.

As already mentioned, the rectangular blanks in stacks with fold lines have to be folded along these lines and be secured together, as is shown in FIGS. 4 and 5 to form a folding structure, e.g., 40. The individual

folding structures can then be joined together in the number necessary for the desired load bearing structure. In the case of load bearing structure of the form shown in FIG. 1, a system of co-ordinates intended for the assembly operation is afforded by the lattice-work formed from the strips 31, 32 and 33 which lattice provides a cell-like structure, with the cells filled with folding structures, e.g., 60 and 70. The folding structures 60 form the corner and side walls of the load bearing structure, whilst the folding structures 70 fill the space enclosed thereby. The folding sections, respectively butting against the lattice-work, of the individual folding structures be connected to the lattice-work, for example also by fastening with the aid of staples, cementing, gluing or the like. The load bearing plate 11 completes the platform. Adjoining this platform, as FIG. 1 shows, are two steps 13 and 14 which are formed from folding structures 40. In the case of this structure, a lattice-work is unnecessary, the contiguous folding sections of the folding structures being directly connected to one another. Also load distributing plates (not shown) will also be placed on the steps.

FIG. 1 shows, that the structures can be stepped at will in their height, according to their purpose.

Shown in FIG. 2 is a platform which is constructed from folding structures directly connected to one another without a lattice-work and which could also, by way of example, be bevelled or stepped. The platform consists of folding structures 40 which form the corners and edges and which are closed on all sides and of which all the internal angles formed by the folding sections are rigidly connected to one another, whilst folding structures 70 enclosed by the folding structures are open on two sides and are rigidly connected, by their parallel folding sections, to the adjacent folding sections.

As is evident from the foregoing, plane load bearing structures formed at will can be erected in a simple manner. It is of great advantage for the different folding structures to be of different colours according to their purpose, to facilitate correct assembly.

I claim:

1. A load bearing assembly, comprising:
a plurality of sheets of corrugated paper consisting of a plurality of parallel fold lines therein, said sheet of corrugated paper being folded along said plurality of parallel fold lines to define a plurality of separate and elongated folded units;

means for securing said folded units in a close side-by-side pattern wherein the longitudinal axes of each of said units are parallel, a side surface of one of said folded units being spaced from the side surface of another adjacent one of said folded units a distance at least equal to the thickness of said corrugated paper; and

a planar load distributing surface means mounted on the ends of said elongated units and extending perpendicular to the longitudinal axes of said folded units.

2. A load bearing assembly according to claim 1, wherein said securing means comprises two sets of upright, corrugated paper members having upper and lower edges and assembled with the members of each set in laterally spaced, parallel relation to each other to define a grid, said folded units being received in the spacing between said sets of members in said grid to maintain the spacing between said folded units.

3. A load bearing assembly according to claim 2, wherein said folded units are identical.

4. A load bearing assembly according to claim 2, wherein said folded units are folded from a sheet of rectangularly shaped corrugated paper.

5. A load bearing assembly according to claim 2, wherein said folded units are composed of a material blank which consists of at least seven folding sections, four of said folding sections are of equal width and are all folded in the same direction each at 90° to form a hollow unit which is quadratic in cross section and open at both ends, a fifth and seventh one of said folding sections being of an equal width and are spaced by a sixth folding section wider than said fifth and seventh folding sections, said fifth, sixth and seventh folding sections being folded into a generally S-shape and positioned inside said folded unit, a first one of said four folding sections being connected to said fifth folded section and a third one of said four folding sections being connected to said seventh folded section.

6. A load bearing assembly according to claim 2, wherein said folded units are composed of a material blank which consists of at least six folding sections, three of said folding sections are of equal width and are all folded in the same direction each at 90°, a fourth and sixth one of said folding sections being of an equal width and are spaced by a fifth folding section which is narrower than said three folding sections, a fourth folding section is folded at 90° to one of said three folding sections, said fifth folding section is folded at an obtuse angle with said sixth folding section and said sixth folding section is connected to said first folding section.

7. A load bearing assembly according to claim 2, wherein said folded units are composed of a material blank which consists of at least three folding sections, a first and third one of said folding sections have the same width and are spaced by a second one of said folding sections which is wider than said first and third folding sections, said first, second and third folding sections being folded into a Z-shape.

8. A load bearing assembly according to claim 2, wherein said folded units are composed of a material blank which consists of at least seven folding sections, four of said folding sections are of equal width and are all folded in the same direction each at 90° to form a hollow unit which is quadratic in cross section and open at both ends, a fifth and seventh one of said folding sections being of an equal width and are spaced by a sixth folding section wider than said fifth and seventh folding sections, said fifth, sixth and seventh folding sections being folded inwardly of said hollow unit, said sixth folding section defines with the fifth and seventh folding sections an obtuse angle, said fifth folding section being connected to one of said four folding sections, said seventh folding section being connected to a second one of said four folding sections.

9. A load bearing assembly according to claim 2, wherein said folded units are composed of a material blank which consists of at least five folding sections, three of said folding sections being of an equal width and are folded in the same direction each at 90°, a fourth and fifth folding section being narrower than said three folding sections, said fourth folding section defines a 90° angle with one of said three folding sections and said fifth folding section defines an obtuse angle with said fourth folding section and a free edge of said fifth folding section is positioned in a corner

formed by the remaining two of said three folding sections.

10. A load bearing assembly according to claim 2, wherein said folded units are composed of a material blank which consists of at least five folding sections, two of said folding sections being of an equal width and are folded to define a 90° angle therebetween, a third and fifth folding section being of a narrower width than an intermediate fourth folding section, said fifth folding section being folded to be parallel to one of said two folding sections and connected thereto.

11. A load bearing assembly, comprising:
a plurality of sheets of corrugated paper consisting of a plurality of parallel fold lines therein, said sheet of corrugated paper being folded along said plurality of parallel fold lines to define a plurality of initially separate and elongated folded units;
means for securing said folded units in a close side-by-side pattern wherein the longitudinal axes of each of said units are parallel, the side surfaces of one of said folded units being connected to the side surface of another adjacent one of said folded units; and
a planar load distributing surface means mounted on the ends of said elongated units and extending perpendicular to the longitudinal axes of said folded units.

12. A load bearing assembly according to claim 11, wherein said folded units are composed of a material blank which consists of at least seven folding sections, four of said folding sections are of equal width and are all folded in the same direction each at 90° to form a hollow unit which is quadratic in cross section and open at both ends, a fifth and seventh one of said folding sections being of an equal width and are spaced by a sixth folding section wider than said fifth and seventh folding sections, said fifth, sixth and seventh folding sections being folded into a generally S-shape and positioned inside said folded unit, a first one of said four folding sections being connected to said fifth folded section and a third one of said four folding sections being connected to said seventh folded section.

13. A load bearing assembly according to claim 11, wherein said folded units are composed of a material blank which consists of at least six folding sections, three of said folding sections are of equal width and are all folded in the same direction each at 90°, a fourth and sixth one of said folding sections being of an equal width and are spaced by a fifth folding section which is narrower than said three folding sections, a fourth folding section is folded at 90° to one of said three folding sections, said fifth folding section is folded at an obtuse angle with said sixth folding section and said sixth folding section is connected to said first folding section.

14. A load bearing assembly according to claim 11, wherein said folded units are composed of a material blank which consists of at least three folding sections, a first and third one of said folding sections have the same width and are spaced by a second one of said folding sections which is wider than said first and third folding sections, said first, second and third folding sections being folded into a Z-shape.

15. A load bearing assembly according to claim 11, wherein said folded units are composed of a material blank which consists of at least seven folding sections, four of said folding sections are of equal width and are all folded in the same direction each at 90° to form a

hollow unit which is quadratic in cross section and open at both ends, a fifth and seventh one of said folding sections being of an equal width and are spaced by a sixth folding section wider than said fifth and seventh folding sections, said fifth, sixth and seventh folding sections being folded inwardly of said hollow unit, said sixth folding section defines with the fifth and seventh folding sections an obtuse angle, said fifth folding section being connected to one of said four folding sections, said seventh folding section being connected to a second one of said four folding sections.

16. A load bearing assembly according to claim 11, wherein said folded units are composed of a material blank which consists of at least five folding sections, three of said folding sections being of an equal width and are folded in the same direction each at 90°, a fourth and fifth folding section being narrower than

said three folding sections, said fourth folding section defines a 90° angle with one of said three folding sections and said fifth folding section defines an obtuse angle with said fourth folding section and a free edge of said fifth folding section is positioned in a corner formed by the remaining two of said three folding sections.

17. A load bearing assembly according to claim 11, wherein said folded units are composed of a material blank which consists of at least five folding sections, two of said folding sections being of an equal width and are folded to define a 90° angle therebetween, a third and fifth folding section being of a narrower width than an intermediate fourth folding section, said fifth folding section being folded to be parallel to one of said two folding sections and connected thereto.
